P. P. GRABOWSKY

BAYONET WIRE CUTTER

Filed Nov. 27, 1920

Peter Paul Grabowsky.

INVENTOR.

BY

Watson E. Coleman

ATTORNEY

UNITED STATES PATENT OFFICE.

PETER PAUL GRABOWSKY, OF PROVIDENCE, RHODE ISLAND.

BAYONET WIRE CUTTER.

Application filed November 27, 1920. Serial No. 426,706.

To all whom it may concern:

Be it known that PETER PAUL GRABOWSKY, a citizen of the United States, residing at Providence, in the county of Providence and State of Rhode Island, has invented certain new and useful Improvements in Bayonet Wire Cutters, of which the following is a specification, reference being had to the accompanying drawings.

10 This invention relates to wire cutters and particularly to bayonet wire cutters.

An object of the invention is to provide a wire cutter of this character which is incorporated in the structure of the bayonet 15 and capable of operating automatically.

Another object is to provide a wire cutter of this character which does not interfere with the use of the bayonet or the attachment of the same to the gun and is so arranged that jamming of the parts is impossible.

Another object of the invention is to provide a wire cutter of this character which is operated by pressure of the gun against the 25 wire to be cut, the pressure of the gun under said circumstances being so great that the wire offers very little resistance so that the cutting is performed without difficulty.

Another object is to provide a wire cutter 30 of this character including a bayonet having a chamber adjacent the hilt in which a pair of wire cutting implements are pivotally mounted, said implements being also pivoted to each other, the pivotal portion of 35 one of the implements serving to bend the wire so as to facilitate cutting when the cutting implement comes in contact with the wire.

Another object of the invention is to provide a novel wire cutter of this character 40 wherein the blade of the bayonet serves as the guide to direct the wire to the cutter and wherein the entrance to the cutter is provided with automatic means to close the entrance after the wire enters the cutter so that it is impossible for the wire to accidentally slip through the entrance, thereby greatly facilitating cutting of the wire.

With the above and other objects in view, 50 the invention consists in the improved construction and arrangement of parts, to be hereinafter more particularly described, fully claimed and illustrated in the accompanying drawings, in which:

55 Figure 1 is a side elevation of a bayonet

wire cutter constructed in accordance with an embodiment of the invention,

Figure 2 is a longitudinal sectional view through the chamber or casing of the cutter,

Figure 3 is a section taken on the line 3—3 of Figure 2,

Figure 4 is a detail view of the jaw members of the cutting mechanism.

Referring to the drawings, A designates a bayonet of the standard type including a gun barrel socket B and a handle C. The inner surface of the socket is lined with insulating material D which insulates the bayonet and the cutting mechanism from the gun barrel in case the cutting mechanism should come in contact with electrically charged wire. The portion 5 of the bayonet at the hilt thereof is enlarged and provided with a downwardly projecting rib 8. The hilt portion of the bayonet is provided with a forward extension, curved and yielding, 65 attached to the handle at its inner end and parallel to and spaced from the handle, adjacent its point of attachment thereto. The space between the rib and the yielding extension forms a compartment. The rib and extension having enlarged inwardly projecting portions extending toward each other.

Disposed within the space or compartment is a novel wire cutting mechanism comprising jaw members 10 and 11. One end portion of the jaw 10 is provided with an extension 12 while projecting from the opposite portion of said end is an enlarged extension 13 which is bifurcated as at 14. The extension 13 is adapted to straddle the lug 8. The extension 12 has its edges canted from the center to the sides of said extension to provide an edge 15 adapted to bend 85 the wire in the cutting operation. It will be noted that the bifurcated extension 13 and the extension 12 extend beyond one side face of the jaw 10. This is to permit the jaws to be pivoted so that the cutting edges 90 thereof are disposed closely adjacent each other. The longitudinal edge of the jaw 10 is canted to provide a cutting edge 16.

The jaw member 11 has opposed bifurcated extensions 17 and 18 which project 105 beyond the front and rear faces of the jaw, said extensions being enlarged and bifurcated, the extension 17 being adapted to straddle the lug 9 while the extension 18 is adapted to receive the extension 12 of the 110

jaw 10. The end wall of the bifurcated extension 18 is provided with a V-shaped groove 19 adapted to receive the bending edge 15 of the extension, while the longitudinal edge of the jaw member 11 is canted to provide a cutting edge 20. The extensions 12 and 18 are provided with the registering openings through which a pin 21 extends to pivotally connect the jaw members. By this means, the jaw members have their cutting edges disposed closely adjacent each other and are arranged if necessary, to pass one another in the cutting operation so that it is impossible for the wire to escape from the cutters without being severed.

The extension 13 is adapted to be pivotally connected to the lug 8 by means of a pivot pin 23, while the extension 17 is adapted to be pivotally connected to the lug 9 by means of the pivot pin 24. It will thus be seen that the jaw members 10 and 11 are not only pivoted to each other but to the portion 5 and the extension 7 so that they are permitted to move longitudinally of the compartment. During this movement the pivot pin moves toward and substantially into alignment with the pins 23 and 24. This naturally causes yielding movement of the extension 7 so as to permit the jaws 10 and 11 to pass each other in the cutting of the wire. A cover or plate 25 is disposed on each side of the opening 6 in the enlarged portion 5, said plates being secured to the bayonet by means of screws 26, 27, 28 and 29. The screws 27 and 28 are disposed above the extension so that they do not interfere with the yielding movement of the extension. The lower portions of the plates extend beneath the extension and are disposed in spaced relation thereto so as not to interfere with the movement of the extension. A spring 30 is disposed within the compartment, and has a portion thereof embracing the screw 29. The end portion 31 of the spring engages the wall of the opening adjacent the hilt of the bayonet while the end portion 32 of the spring is curved towards the hilt of the bayonet and adapted to engage the end portions 33 and 34 of the jaw members 10 and 11, said portions preventing contact of the spring with the edge of the extension 12. By this means the jaws are normally held in spaced relation to each other, or in other words, are in position to receive a wire. The screws 26 and 27 are adapted to engage the outer surface of the jaws 10 and 11 respectively to limit pivotal movement of said jaws away from each other under pressure of the spring 30.

Each of the plates 25, is provided with an elongated slot 35 which extends from the extension 7 of the enlarged portion 5 and terminates slightly beyond the intermediate portions of the opening or cham-

ber. This opening is relatively wide so as to accommodate wires of various gauges. To prevent accidental disengagement of the wire that has entered the slots 35, there is provided a novel closure member comprising an arm 36 which is pivoted at its end 37 between the forward ends of the plates 25, the end 39 and upper portion 40 of the arm being sharpened. The end 39 is provided with a roller 39^a adapted to move in a slot 40^a provided in the portion of the blade A within the chamber so as to guide the arm 36. A spring 41 is secured at one end to the rear face of the arm 36 and at its other end to the portion of the enlarged portion 5 adjacent the extension 7. It will be noted that the last mentioned portion, and the forward ends of the plates project beneath the end portion of the bayonet blade A so that the sharp edge of said blade at this point cooperates with the sharpened portions 39 and 40 of the arm 36 to efficiently guide the wire into the chamber formed through the cooperation of the plates 25 and the opening 6.

In the operation of the device, the wire will engage the lower edge of the blade A and be directed thereby into contact with the arm 36. The pressure or weight of the user upon the gun will cause the wire to swing the arm 36 downwardly, and pass into the chamber transversely of the plates 25, portions of the wire extending through the slots 35. Continued forward movement of the user will cause the wire to pass between the jaw members 10 and 11 into engagement with the bending edge 15 whereupon the pressure of the operator on the gun will cause the wire to move the jaw members 11 and 10 toward each other. This pivotal movement, of the jaw members 10 and 11 will cause the sharpened edge 15 of the extension to bend the wire thereby causing the jaw 11 to urge the extension outwardly to permit severing of the wire. It is of course obvious that the pressure of the user against the wire is greater than the strength of the spring 30 so that the wire may be readily severed. After the wire has been severed the severed portions pass rearwardly over the end walls of the slots 35.

After the wire enters the chamber and comes in contact with the bending edge 15, the movement of the jaw members toward each other will substantially cause the lower portion of the chamber to extend outwardly, in view of the fact that it is separated from the upper portion or body portion of the bayonet, by the opening 7. This movement will cause the roller to move so as to properly enter the slot 40^a through the medium of the spring 41 so that if the wire is not cut upon the first thrust of the gun, the user may move the gun rearwardly so as to permit the jaws to obtain

a new hold upon the wire. In this event, the arm 36 prevents disengagement of the wire from the chamber, and also eliminates the necessity of the user holding the gun 5 substantially in an inclined or vertical position to prevent accidental disengagement of the wire from the chamber of the cutter. After the wire has been cut, the severed portions of the wire, pass toward the hilt 10 of the bayonet whereupon the pressure of the spring 30 will force the jaw members 10 and 11 forwardly thereby opening the jaws.

From the foregoing it will be readily 15 seen that this invention provides a novel form of wire cutter wherein the cutting operation is performed similar to a pair of shears held in the hand, but without requiring the user to move the cutters toward 20 each other. All that is necessary is for the user to grasp the gun firmly, the cutting members do the rest automatically.

What is claimed is:—

1. A bayonet wire cutter comprising a 25 body member having a chamber and an entrance opening extending through one end in the sides of the chamber, a pair of jaws, each jaw having bifurcated extensions on one end, said extensions projecting in opposite directions, one of the extensions of each jaw being engaged with each other, the remaining extension of each jaw being pivoted to the body member, one having yielding support and a spring carried by 30 said body member, said spring urging the cutting edges of the jaws away from each other.

2. A bayonet wire cutter comprising a body member having a chamber and an 40 entrance opening extending through one end in the sides of the chamber, a pair of jaws, each jaw having bifurcated extensions on one end, said extensions projecting in opposite directions, one of the extensions of 45 each jaw being pivoted to the adjacent extension of the opposite jaw, the remaining extension of each jaw being pivoted to the body member, one having yielding support and a spring carried by said body member, 50 said spring urging the free ends of the jaws away from each other, whereby the pressure of a wire inserted in the chamber and be-

tween the jaws will move the jaws toward each other.

3. A wire cutter comprising a body member having a yielding extension disposed closely adjacent the body member, the end portion of the extension and adjacent portion of the body member being vertically spaced to provide a recess with recesses 55 which coact to provide a compartment, cutting means comprising a pair of pivotally connected jaws, said jaws having extensions, the extension of one jaw being pivoted to the body member in the recess, the extension of the remaining jaw being pivoted to the extension of the body member, and means carried by the body member within the compartment for urging the jaws 60 away from each other, the extension of the body member being movable according to the movement of the pivotal connection of the jaws to each other.

4. A wire cutter comprising an elongated yielding extension extending substantially 75 in parallel relation thereto, the extension forming with an adjacent portion of the body member, a recess, a pair of jaw members pivotally connected to each other at one of their ends, said jaw members having 80 shanks extending in opposite directions, the shank of one of said jaw members being pivoted to the body member in the recess, the shank of the remaining jaw member being pivoted to the extension, means carried 85 by the body member and disposed within the compartment for normally holding the pivot of the jaws to one side of the aligned pivots of the shanks of the jaws, plates carried by the side portions of the body 90 member and the extension and cooperating to provide a chamber, said plates having longitudinally extending slots coacting to provide a guide, the lower portion of said plates extending beneath the extension in 95 spaced relation to the extension whereby said extension is capable of adjusting itself within the chamber according to the movement of the pivot of the jaws relative to the pivots of the extensions of the jaws. 100

In testimony whereof I hereunto affix my signature.

PETER PAUL GRABOWSKY.
